UNITED STATES PATENT OFFICE.

HORACE H. TAYLOR, OF SAN JOSE, CALIFORNIA, ASSIGNOR OF ONE-HALF
TO FRANK J. MAYHEW, OF SAN FRANCISCO, CALIFORNIA.

REFLECTOR FOR HEAD, SEARCH, OR OTHER LIGHTS.

SPECIFICATION forming part of Letters Patent No. 731,084, dated June 16, 1903.

Application filed November 5, 1902. Serial No. 130,163. (No model.)

To all whom it may concern:

Be it known that I, HORACE H. TAYLOR, a citizen of the United States, residing at San Jose, in the county of Santa Clara and State of California, have invented certain new and useful Improvements in Reflectors for Head, Search, or other Lights; and I do hereby declare that the following is a full, clear, and exact description of the same, reference being had to the annexed drawings, making a part of this specification, and to the letters of reference marked thereon.

The present invention has relation to the mirrors or reflectors for head, search, or other lights which are adapted for use on locomotives, street or other cars, automobiles, and all classes of vehicles and places where the same would be found useful; and the purpose of the invention is to provide a mirror or reflector that will be simple in construction and in which the rays of light may be spread or contracted or otherwise controlled, and is designed as an improvement upon my former patent, dated August 26, 1902, and numbered 25 707,982.

The invention consists in a mirror or reflector for head, search, and other lights constructed substantially as shown in the drawings and hereinafter described and claimed.

Figure 1 of the drawings is a front elevation of a mirror or reflector for head, search, or other lights embodying my invention; Fig. 2, a rear elevation thereof; Fig. 3, a central sectional elevation taken on line 3 3 of Fig. 35 2; Fig. 4, a horizontal section taken on line 4 4 of Fig. 2; Fig. 5, a detail view of a portion of one of the adjustable parte-sections of the mirror or reflector, showing its pivotal connection upon its back or rear side.

In the accompanying drawings, A represents the mirror or reflector for head, search, or other lights, said mirror or reflector being concavo-convex in form and placed in an upright position back of the light when used.

This mirror or reflector is formed with suitable spaces, which extend from its outer periphery or edge and gradually decreasing in width in a direction toward the center thereof, forming what may be termed "fan-shaped" spaces. In these spaces are located

respond to that of the spaces; but in the present instance, however, I have shown the sections in the form of parte-sectors B and the spaces to correspond therewith. The parte-sectors when in place assist in completing a circular concavo-convex mirror or reflector, as shown in Fig. 1 of the drawings, and said parte-sectors are provided with suitable means whereby their position may be changed 55 or adjusted with relation to the mirror or reflector, so as to vary the angle thereof to control the rays of light.

Suitable lugs *a* project from the back or rear side of the adjustable parte-sectors B to 65 enable a pivotal connection to be made between the same and a suitable standard or supporting-frame, said standard or frame having arms *b*, which are pivotally connected to the lugs by means of pivot-pins *c*.

Any suitable and well-known means may be employed to form a pivotal connection between the parte-sector and the standard or supporting-frame, that shown being one of many means that may be resorted to to attain 75 this end.

The stationary or immovable mirror or reflector A is connected to a central hub D, having exterior screw-threads thereon, said hub being connected to an interior screw-threaded 80 sleeve or ring *d*, forming a part of the standard or frame C.

I do not desire to limit my invention to any particular means of supporting the stationary or immovable mirror or reflector, as this 85 may be left to the judgment of those using the device.

The standard or frame C may be connected to any stationary object, as indicated at E, and back-supports are provided for the stationary or immovable mirror or reflector A through the medium of suitable braces *f*, secured to the part *g* of the base or other object E, and a brace *h* is also provided for the upper portion of the stationary or immovable 90 mirror or reflector. This bracing and supporting of the stationary segments may be accomplished in various ways, and it is not essential that the means shown should be employed.

Suitable set-screws *i* or other desirable means may be provided for holding the

screw-threaded hub D stationary after being screwed into the sleeve or ring d , as shown in Fig. 2 of the drawings.

Upon the back or rear side of the adjustable parte-sectors B are slotted or bifurcated brackets F, with which engage cam devices G, said cam devices projecting from the outer ends of suitable arms H, which arms in turn project from a central collar I, movable upon the hub D. This collar is held upon the hub by means of a ring j and set-screw k, as shown in Figs. 2 and 3 of the drawings, or any other suitable means may be provided for holding the collar on the hub as found best adapted to the purpose. The collar I is caused to move upon the hub D by means of a suitable lever J, depending from said collar, as shown in Figs. 2 and 3 of the drawings, and connected to this lever may be any suitable means for operating the same whereby the lever may be moved by any power found most convenient—such as electricity, steam, air, or hand-power—this being left entirely optional with the user or as conditions should require.

To reinforce and strengthen the stationary or immovable mirror or reflector A, the back thereof is provided with strengthening-flanges l, as shown in Fig. 2 of the drawings, or any other suitable means may be provided whereby the stationary or immovable mirror or reflector may be strengthened.

The movable parte-sectors B are pivotally connected to the arms of the stationary standard or supporting-frame C and the cam device G, engaging the bifurcated brackets F. It will be seen that by moving the arms carrying the cam devices said devices will be moved and through their engagement with the bifurcated brackets the parte-sectors B will be moved either in or out, as the case may be, thereby changing the position of the movable parte-sectors with relation to the stationary or immovable mirror or reflector, thus controlling the rays of light as circumstances would require.

The mirror or reflector herein described may be used in connection with arc-light or other electric-light producing medium, or any light of whatever character may be used in connection with the mirror or reflector.

It will be seen that the mirror or reflector, with its adjustable sections, which in the present instance I have shown as in the form of parte-sectors, form together a complete up-right concavo-convex mirror or reflector in which the reflecting-surface is complete and unbroken, the parte-sectors nicely fitting in the spaces formed in the main mirror or reflector.

6c The mirror or reflector proper is stationary or immovable and the sections or parts-sectors, which fit in the spaces of said mirror or reflector, are movable, the two when together forming a complete circular mirror or reflector.

I do not wish to be understood as limiting

my invention to any special number of the movable sections or parte-sectors or the manner in which the same may be adjusted, this not being considered essential to the successful operation of the mirror or reflector. Consequently any changes or modification that would suggest themselves to ordinary mechanical judgment may be resorted to without affecting the essential features of the invention. 75 70

In describing the several mechanical devices necessary for the support of the stationary or immovable mirror or reflector and the mechanical devices or mechanism employed for controlling the movement of the sections or parte-sectors I do not desire to confer the impression that such devices or mechanism may not be substituted by others equally as practicable, and therefore reserve this right to change or modify the same as circumstances would require. 80 85

Having now fully described my invention, what I claim as new, and desire to secure by Letters Patent, is— 90

1. A stationary reflector for head, search, and other light, said reflector having spaces extending from the periphery thereof and decreasing in width in a direction toward its center, and suitable adjustable sections located in said spaces to form a complete unbroken reflecting surface to the reflector, substantially as and for the purpose set forth. 95

2. A stationary reflector for head, search, or other light, and adjustable parts-sectors located in correspondingly-formed spaces in the reflector, substantially as and for the purpose specified. 10c

3. A reflector for head, search, or other light, and pivoted parte-sectors located in 105 correspondingly-formed spaces in the reflector, and suitable means for operating the same, substantially as and for the purpose described.

4. A reflector for head, search, or other 110
light, pivoted parte-sectors located in corre-
spondingly-formed spaces in the reflector,
cam devices connecting with the parte-sectors,
and suitable means connecting with the cam
devices, whereby the parte-sectors are oper- 115
ated and controlled, substantially as and for
the purpose set forth.

5. A reflector for head, search, or other light, pivoted sections located in spaces formed in the reflector, suitable brackets upon the pivoted sections, and suitable cam devices connecting therewith, whereby the position of the pivoted sections may be adjusted and regulated, substantially as and for the purpose specified. 120 125

In testimony whereof I affix my signature
in presence of two witnesses.

HORACE H. TAYLOR.
